FIG. 16

UNITED STATES PATENT OFFICE.

ARTHUR RYAN RICE, OF TORONTO, ONTARIO, CANADA.

ELECTRIC SWITCH.

Application filed January 28, 1925. Serial No. 5,326.

The invention relates to improvements in electric switches as described in the present specification and illustrated in the accompanying drawings that form a part of the 5 same.

One object of the invention is to provide an efficient pull chain mechanism which may be readily mounted in the smallest size of shell of the chandelier type of switch now 10 used, thus eliminating the necessity of two sizes of sockets, which has hitherto been a requirement due to the smaller sockets, which are in much demand owing to their more attractive appearance, not being efficient in operation and thus heretofore making a necessity the manufacture of a larger mechanism for more universal use.

Another object is to provide a pull chain switch operable by means of a toggle mechanism, which insures a more positive action 20 than any other means.

A further object of the invention is to make possible the production of a switch of the pull chain type at as low a cost as that of 25 the button socket.

A still further object is to provide a switch in which the upper and lower porcelain parts are similar in construction and consequently interchangeable.

And generally the objects of the invention are to provide an electric switch which will 30 be simple and inexpensive to construct, positive in action, neat in appearance and durable.

The invention consists of a frame suitably insulated and having permanent contact elements incorporated therewith, an operating element including means for removably supporting a pull member, a movable switch 40 element pivoted for rotation on a horizontal plane in guide slots in said frame, a bracket pivotally supported by said operating element and adapted to be brought into operative engagement therewith during one phase 45 of the movement, a compression spring connecting said movable switch element and said bracket and on the rotation of said bracket moving said switch element to its alternate position by snap action, and a latch device 50 cooperating with said operating element and said bracket to lock same together subsequent

to each movement of said switch element, and including means for reversing the direction of travel of the switch movement.

In the drawings Figure 1 is a side elevation of a switch in its assembled condition.

Figure 2 is a cross sectional view taken substantially on the line A—A of Figure 4, with the circuit through the switch closed.

Figure 3 is a cross sectional view taken substantially on the line B—B of Figure 4 with the circuit broken.

Figure 4 is a central vertical sectional view through a switch taken in the neutral position of the spring during operation.

Figure 5 is a plan view of one of the porcelain parts with the binding posts in position.

Figure 6 is a vertical sectional view taken on the line C—C of Figure 5.

Figure 7 is a plan detail of the horn.

Figure 8 is a longitudinal sectional view taken on the line D—D of Figure 7.

Figure 9 is an end view of Figure 7.

Figure 10 is an assembled detail of the 75 spring and its mounting, parts of which are shown in longitudinal section.

Figure 11 is a detail in perspective of the latch device.

Figure 12 is a detail in perspective of the 80 bracket adapted to support the device shown in Figure 11.

Figure 13 is a plan view of the device to which the chain is secured.

Figure 14 is a longitudinal sectional view 85 taken on the line E—E of Figure 13.

Figure 15 is an inner side view of the movable switch element.

Figure 16 is a cross sectional view taken on the line F—F of Figure 15.

Figure 17 is an assembly view in plan of a modified form of construction.

Figure 18 is a longitudinal sectional view taken on the line G—G of Figure 17.

Like numerals of reference indicate corresponding parts in the various figures.

Referring to the drawings 1 and 2 are discs constructed from porcelain or other insulating material and between which the switch movement is adapted to be mounted, 100 said discs being identical in construction and therefore interchangeable and being secured

in spaced relation by means of the binding posts 3 and 4, over the inner faces of which are secured stop members 5 which project past the side edges of said posts, said members being constructed of insulating material.

6 and 7 are the permanent contacts carried by the discs 1 and 2 respectively, the contact 6 being in the form of a screw extending 10 through the base member 1 and the contact 7 being in the form of an integral foot or projection from the binding post 4, but it must be understood that said contact 7 may be in the form of a separate member suitably connected in the circuit if desirable.

A is the movable switch element, or arm, consisting of a vertical wall, or end piece 8, having outward extensions 9 from the top and bottom edges adapted to slide in curved 20 guide slots 10 in the inner faces of the discs 1 and 2 respectively, and integral parallel arms 11 extending at right angles to said end 8 and provided with openings 12 adjacent to the ends thereof adapted to encircle 25 pivot members 13 with which the discs 1 and 2 are provided to permit of said switch arm rotating on a horizontal plane to and from its operative position, said arms being provided with opposed integral extensions, 30 or fingers, 14 adapted on the rotation of the switch arm to engage the permanent contacts 6 and 7 and thus close the circuit through the switch.

B is an operating element comprising a 35 substantially semi-inverted cone shaped device 15 from which extend at right angles thereto flat arms 16 and 17 which are rotatably mounted on a vertically arranged pivot 18 suitably mounted at its ends in the 40 discs 1 and 2 respectively at a point removed from the slot 10 in which the switch element A operates and opposed thereto, the lower arm 16 being somewhat longer than the arm 17 and being enlarged to provide a circular 45 disc like end 19, and the arm 17 being cut away at its end to provide oppositely disposed shoulders 20 projecting forwardly at an angle of substantially 45 degrees.

The hollow cone shaped portion of the 50 frame B is provided with a substantially key hole shaped opening 21 in the top wall thereof terminating in a cross end slot 22, said slots being for the purpose of removably securing the chain C to the switch movement, the enlarged portion of the slot 21 permitting of the ball, or other end enlargement, 23 of the chain being inserted in the interior of the cone, which constitutes a seat therefor, and the cross slot 22 which loosely 55 accommodates the link 24 permitting of the easy operation of the chain in a lateral direction.

25 is a bracket, in side elevation being in the form of a substantially rectangular hollow frame, said bracket being provided with

upper and lower extensions 26 constituting bearings extending into openings 27 in the arms 16 and 17 respectively of the frame B and permitting of said bracket rotating, or swinging, on a horizontal plane from side to side of the pivot 18 in alternate movements of the member B, said bracket being cut away along its under side to provide a shoulder 28 adjacent to the bearing 26 and also being provided with a forwardly and 75 downwardly extending foot 29, said bracket being provided also at its top forward end with an enlargement, or shoulder, 30 adapted, on the rotation of said bracket to abut one, or other, of the shoulders 20 of the arm 17, according to the direction in which said bracket is rotated, to prevent further rotation thereof.

31 is a latch member comprising a circular disc rotatably supported above the arm 16 of the frame B in slightly spaced relation thereto by means of the foot, or extension, 29 of the bracket 25 extending through an opening 32 located to one side of the centre thereof, said disc being provided with a finger 33 projecting outwardly from a point adjacent to the opening 32 and adapted on the operation of the switch movement to be brought into engagement with one, or other, of the stop members 5, according to the direction in which said movement is rotated, for the purpose of limiting the rotation of said movement and for reversing the direction of travel of said disc, as will be described more fully hereinafter.

The latch member 31 is provided with an enlarged central opening 34 through which extends the pin 18 on which the operating element B is mounted, said opening being shaped to provide a central curved wall 35 105 providing inwardly projecting shoulders 36 extending into the path of the shoulder 28 in the rotation of the bracket 25 to cause coincident rotation of said disc and said frame B, when said frame is rotated by 110 pulling on the chain C, said shoulders 36 receding outwardly to provide opposed circular recesses 37 adapted on alternate movements of the switch to be brought into register with said pin 18 which acts as a stop to prevent further rotation of said disc, said opening 34 being extended rearwardly to a point adjacent to the edge of the disc to provide sufficient room for the free rotation of the disc around said pin 18.

38 is a helical compression spring connecting the vertical wall 8 of the switch element A and the forward end 39 of the bracket 25 and being adapted on the rotation of said bracket to move said switch arm with a snap action to, or away from, the permanent contacts, according to the direction in which said bracket is rotated through the movement of the element B, said spring being mounted on a cylinder 40 having a fork 125 130

shaped end 41 fitting the upright 39 and a plunger 42 having a rounded head 43 fitting into a concaved cap 44 mounted in an opening in the wall 8 of the switch element, said 5 cap being suitably insulated from said wall by means of a sheet 45 of suitable insulating material.

46 is a threaded lamp screw shell secured in any suitable manner to the outer face of 10 the disc 1.

47 is the horn which is constructed of two sections, each of which is provided with oppositely disposed extensions 48, the extension from one side of one of said sections and the 15 extension from the opposite side of the other of said sections being provided with offset portions 49 adapted to overlap the respective adjacent extensions to secure the sections together, said extensions, or lugs, being 20 adapted to be inserted in slots 50 in the discs 1 and 2 respectively, the inner walls 51 of said slots being tapered to permit of the easy removal of the chain from its seat in the element B.

25 52 is the enclosing shell which is provided with a suitable lining 53 of insulating material, both shell and lining being cut away to permit of the projection of the horn 47, a cap 54 having suitable means for securing 30 same to the shell being also provided.

In the close condition of the switch the various elements of the movement are in the positions shown in Figure 2, the movable and permanent contacts being in engagement and 35 the spring 38 extended and holding the finger 33 of the disc 31 in engagement with the stop 5 farthest removed from said movable contact, the bracket 25 and the operating element B being securely locked together 40 for coincident movement by means of said disc which has taken up a position with the shoulder 36 on the side nearest to said movable contact engaged by the shoulder 28 of 45 said bracket and the pivot 18 in the corresponding side recess 37.

In the operation of the invention, when it is desired to move the switch element A to its alternate position from that shown in Figure 2 it is simply necessary to rotate the 50 operating element B by pulling on the chain C and as the bracket 25 and the operating element are locked together by means of the disc 31 said bracket will be rotated against the pressure of the spring 38, compressing 55 same and also bringing the inner end of same across a straight line drawn between the point of connection between said spring and the switch element A and the pivotal point 26 of said bracket, subsequent to which 60 the spring assumes control and snaps the contact element A to its inoperative position, also forcing the outer end of said bracket backwardly, which through its pivotal connection 29 with the disc 31 rotates 65 said disc until the finger 33 strikes against

the obstruction 5, after which the disc is prevented from further forward rotation, but as the pressure of the spring on the bracket 25 continues the result is that said bracket is forced backwardly against its connections 29 70 and 26 with the disc 31 and operating element B respectively which has the effect of rotating the outer end 15 of said element B in a direction towards the spring 38 in its new position and also reversing the direction 75 of rotation of the disc 31 and causing same to swing across the portion 19 of said operating element and take up its position with the shoulder 36 abutting the shoulder 28 of said bracket and the recess 37 encircling the pin 18, in which position the bracket 25 and the operating element B are locked for the next operation. In the rotation of the bracket 25 the shoulder 30 thereof engages the corresponding side shoulder 20 of the 80 arm 17 of the operating element just prior to the engagement of the finger 33 with the obstruction 5 so as to absorb a portion of the shock and also to add impetus to the 85 subsequent rotary movement of the operating element to its alternate position.

It will have been noticed that the recesses 90 37 in the disc 31 are much greater in circumference than the pivot 18 and this difference is for the purpose of allowing play between the elements to provide flexibility in 95 operation.

When it is desired to remove the chain it is simply necessary to remove the outer shell 100 of the device and also the horn 47 and to rotate the operating element B until the opening 21 in the outer end thereof is directly beneath the slot 50 in the disc 2, in which position the ball 23 can be withdrawn 105 from said opening.

In Figures 17 and 18 a modified form of construction is shown in which two latch discs are employed mounted on extensions from the upper and lower edges of the bracket 25, said discs respectively being provided with circular slots 56 terminating at their ends in enlarged portions 57 for the reception of the pin 18 in the alternate positions of said discs, said pin 18 extending through substantially key hole shaped slots 110 58 in the arms of the operating element B.

The method of supporting the spring in a telescopic mounting, including the method of countersinking the head of the plunger 115 42, and the general construction of the various parts permits of the use of a toggle mechanism in a smaller size of shell than heretofore has been possible.

The manner in which the chain is secured 120 to the switch movement is a most important feature, permitting, as it does of removing the chain without interfering in any way with the switch movement.

What I claim is:—

1. In an electric switch, a switch element 130

- movable on a horizontal plane from one to its alternate position, an operating element reciprocable on a horizontal plane from one to its alternate position and comprising a 5 body portion and spaced superposed arms rotatably mounted on a vertical bearing fixedly mounted in said switch, a bracket pivoted in said arms adjacent to said bearing and extending therebeyond, a compression spring connecting said switch element and the outer end of said bracket, a latch plate pivotally supported by an extension from the outer end of said bracket and provided with means to operatively connect 10 said bracket and said operating element whereby on the rotation of said operating element said spring is compressed, insulated stop members carried by said switch in opposed relation to each other, a finger carried by said latch plate and engaging alternate stops in the movement of the switch, means whereby on the engagement of said finger with the adjacent stop the pressure of said spring moves said latch plate and said 15 operating element to their alternate positions in operative engagement with one another, and a pull member carried by said operating element.
2. In an electric switch, a switch element pivoted for rotation to and fro on a horizontal plane, means to move said element from one to its alternate position by snap action, said means including a horizontally rotatable operating element, a bracket pivotally supported by said operating element, a spring connection extending from said switch element to said bracket, latch means interposed between said operating element and said bracket and including a finger adapted to engage said stops alternately to 20 limit the rotary movement of said switch element, and means for temporarily freeing said bracket and said operating element from locking engagement for a period during each operation of the switch movement.
3. In an electric switch, a switch element pivoted for rotation to and fro on a horizontal plane, means to move said element to its alternate position by snap action, said means including a horizontally rotatable operating element, a bracket pivotally supported by said operating element, a spring connection extending from said switch element to said bracket, latch means including 25 a disc pivoted to said bracket beyond said operating element and operating around the bearings of said bracket and said operating element and being provided with interior opposed shoulders having corresponding recesses, said disc being movable in the operation of the switch movement to alternately bring said shoulders and their corresponding recesses into register with the bearings of said bracket and said operating element respectively to operatively connect said 30 bracket and said operating element, said disc being provided with a stop finger, and stop members positioned in the path of said finger and reversing the direction of travel of said disc to move same to its alternate position subsequent to the conclusion of the movement of said switch element.
4. In an electric switch, a switch element pivoted for horizontal rotation to and fro, means to move said element to its alternate position by snap action, said means including an operating element pivoted for rotation on a horizontal plane, a bracket having a fixed pivot rotatable in said operating element, said bracket in operation moving to 35 alternate sides of the bearing for said operating element upon successive operations of the switch, a compression spring connecting said switch element and said bracket, a latch plate pivotally supported by said bracket and provided with means to operatively connect said bracket and said operating element whereby on the rotation of said operating element said spring is compressed, stop elements carried by said switch on opposite sides of said operating element, said latch plate including a finger engaging said stops alternately to limit the rotary movement of said brackets, and means whereby 40 on the engagement of said finger with the adjacent stop the pressure of said spring moves said plate and said operating element to their alternate positions in operative engagement with one another.
5. In an electric switch, a movable switch element, an operating element rotatable around a fixed bearing, a bracket pivotally mounted in said operating element and in each operation of the switch swinging across said bearing, a spring connecting said switch element and the free end of said bracket, and means interposed between said operating element and said bracket whereby in the initial part of the movement of the switch said bracket is rotated, through the 45 operation of said operating element, against the pressure of said spring to compress same and move same across a straight line between the point of connection with said switch element and the pivot point of said bracket, and whereby in the latter part of the movement of the switch said bracket and said operating element are temporarily freed from locking engagement through the pressure of said spring on said bracket, said means including a stop finger engaging the 50 switch frame to limit the movement of said bracket, said means also including means for relocking said bracket and said operating element subsequent to each movement of said switch element.
6. In an electric switch, a movable switch element, a rotatable operating element, a bracket pivotally supported by said operating element and swinging clear thereof, a 55

- spring connecting said switch element and the free end of said bracket, means for locking said bracket to said operating element to provide for coincident rotation to 50
5 press said spring and move same across a straight line drawn between the point at which said spring is connected to said switch element and the pivot point of said bracket, said means including a centrally 70
10 slotted disc rotatably mounted on an extension from the free end of said bracket and rotating around the bearings of said bracket and said operating element, the inner wall of said disc being shaped to provide shoulders 75
15 positioned on opposite sides of the bearing for said bracket and corresponding recesses, said shoulders and their corresponding recesses respectively being adapted for engagement by said bracket and said bearing 80
20 on which said operating element is mounted respectively in alternate positions of the switch movement, means for freeing said bracket and said operating element from locking engagement during each operation 85
25 of the switch to permit of said bracket and said operating element moving to their alternate positions, and means for relocking same for subsequent operation.
7. In an electric switch, a housing including 30
30 a pair of disc like elements secured in spaced parallel relation to each other and recessed interiorly to receive the switch movement, permanent switch contacts, a horizontally rotatable switch element adapted to be brought to its alternate position 90
35 by snap action, said switch element comprising a vertical body portion and horizontally disposed integral arms rotatably mounted in bearings from the inner faces 95
40 respectively of said discs and carrying yieldable contact pieces integral therewith, means to move said element to and from its operative position by snap action, said means including a horizontally rotatable operating 100
45 element, a bracket pivotally supported by said operating element and swinging alternately to opposite sides of the pivot point of said operating element, a spring connecting said vertical wall of said switch element and the outer end of said bracket, latch means interposed between said operating element and said bracket, and means for reversing 105
50 movement of said switch element.
8. In an electric switch, a housing including 110
55 a pair of disc like elements secured in spaced parallel relation to each other and recessed interiorly to receive the switch movement, permanent switch contacts, a horizontally rotatable switch element adapted to be brought to its alternate position by snap action, said switch element comprising a vertical body portion and horizontally disposed integral arms rotatably mounted in 115

- bearings from the inner faces respectively of said discs and carrying yieldable contact pieces integral therewith, means to move said element to and from its operative position by snap action, said means including a horizontally rotatable operating element, a bracket pivotally supported by said operating element and swinging alternately to opposite sides of the pivot point of said operating element, a spring connecting said vertical wall of said switch element and the outer end of said bracket, a latch member interposed between said operating element and said bracket, stop members positioned in the path of said latch member for arresting the forward movement of said latch member subsequent to the conclusion of movement of said switch element, whereby the pressure of said spring is concentrated on the inner portion of said bracket to move said latch member and said operating element to their alternate operating positions, and a pull member removably secured to said operating member.
9. In an electric switch, a housing comprising spaced parallel discs interiorly recessed to receive the switch movement, binding posts connecting said discs, permanent switch contacts, a horizontally rotatable switch element including a vertical wall having projections operating in guide slots in said discs, means to move said switch element to its alternate position by snap action, said means including a horizontally rotatable operating element, a bracket supported by said operating element and projecting therebeyond, the pivot point of said bracket being adjacent to the bearing of said operating element, said bracket in operation swinging alternately to opposite sides of said bearing, a telescopic spring mounting connecting the vertical wall of said switch element and the free end of said bracket, and insulated from said wall, a spring encircling said mounting and exerting pressure on said bracket, latch means interposed between said operating element and said bracket and providing coincident movement thereof to move said bracket to its alternate position, and means for reversing said latch means.
10. In an electric switch, a housing, permanent contacts, a horizontally rotatable switch element movable from one to its alternate position by snap action, an operating element including horizontally disposed spaced parallel members rotatably mounted on a fixed bearing connecting said discs and an integral member in substantially semi-inverted cone shape connecting the outer ends of said members, said intermediate member being provided on its top side with a substantially key hole shaped opening terminating in a cross end slot to removably support a pull member, the outer end of the

upper horizontal member of said operating element being cut away to provide opposed shoulders, a bracket pivotally supported by said operating element and projecting therefrom beyond, the pivot point of said bracket being adjacent to said fixed bearing, said bracket in operation swinging alternately to opposite sides of said fixed bearing and terminating in engagement with the corresponding shoulder of said operating element, a spring connecting said switch element and the free end of said bracket, latch means carried by the free end of said bracket and interposed between said bracket and said operating element, and a pull member.

11. In an electric switch, a housing comprising members constructed of insulating material rigidly connected in spaced parallel arrangement, permanent contacts supported from the opposed faces respectively of said housing, a switch element comprising a vertical body portion and superposed spaced parallel arms pivoted on bearings from the opposed faces of said housing, said arms being provided with yieldable extensions constituting contact members, said switch ele-

ment being rotatable on a vertical plane towards and away from said permanent contacts, an operating element rotatable on a horizontal plane from one to its alternate position, a bracket pivoted in said operating element and having yieldable connection with the body of said switch element, a latch member carried by said bracket and adapted to operatively connect said bracket and said operating element, said latch member being shiftable in relation to said operating member, through the operation of said yieldable connection to lock said bracket to said operating element on each movement of the switch element, means for reversing the direction of rotation of said latch member, a pull member removably secured to said operating element, a horn supporting said pull member, said horn comprising two sections adapted to be secured together in overlapping arrangement, an enclosing shell, and insulating elements.

Signed at the city of Toronto, Ont., this sixteenth day of January, 1925.

ARTHUR RYAN RICE.
